LIQUID FUEL INJECTING BURNER

Kenneth William Jay, Toronto, Ontario, Canada,
assignor to A. V. Roe Canada Limited, Malton,
Ontario, Canada, a corporation

Application April 12, 1950, Serial No. 155,525

3 Claims. (Cl. 60—39.71)

1

This invention relates to combustion systems in which a liquid fuel is vapourized before being admitted to the combustion zone and more particularly to burners associated with such systems.

A commonly-used type of vapour combustion system embodies a vapourizer comprising a group of tubes extending into a combustion chamber and through which a liquid fuel or a mixture of liquid fuel and air is directed into the combustion chamber. The tubes are exposed externally to the burning gases within the chamber, and the liquid fuel flowing through the heated tubes is vapourized before entering the combustion zone; the vapourization of the fuel produces a pronounced cooling effect upon the tubes which protects them against burning.

In order to provide a relatively uniform distribution of the combustible vapour in the combustion zone and at the same time an adequate vapourizing surface, it is customary to employ a number of vapourizer tubes suitably disposed in the combustion chamber, and it is desirable that the quantity of fuel fed into each tube of the group should be closely controlled so that the distribution of fuel between the tubes may be uniform. To this end fuel is introduced to the group of tubes from a central burner in which is mounted a number of calibrated jets or nozzles, each injecting fuel, at a common supply pressure, into one tube of the group.

The jets or nozzles heretofore employed are unitary members which are difficult and costly to manufacture because of the accuracy with which the jets must be made in order to ensure uniformity. Furthermore, mounted as they normally are on the outside of the body of the burner, such prior art jets are easily damaged, and their calibration may even be affected by rough handling during assembly.

The main object of this invention is to provide a burner of such construction that the jets may be readily manufactured in quantity within close tolerances and may be installed in the burner without risk of distortion.

Another object of the invention is to provide adequate protection for the individual jets against accidental damage which may affect their calibration.

Other objects and advantages of the invention will be apparent from the following description of a typical embodiment thereof.

In the drawings which form a part of this application, and in which like reference characters designate like parts throughout:

Fig. 1 is a view in side elevation, partly broken 55 through a hollow boss 20 which opens into a

2

away, of a vapour system burner constructed in accordance with this invention, shown installed in a typical gas turbine engine, the burner and more relevant portions of the engine being shown in heavy lines;

Fig. 2 is an enlarged view partly in section, of the vapour system burner and adjacent vapourizer tube assembly;

Fig. 3 is an enlarged sectional view of the vapour system burner and adjacent portions of the vapourizer tubes; and

Fig. 4 is an exploded perspective view of the jet plate and of the jets.

The vapourizer system illustrated comprises a burner constructed in accordance with the invention, and generally indicated by the reference numeral 5, and a group of vapourizer tubes 6, one such vapourizer system being disposed within each of a number of flame tubes 7. According to well known practice, the flame tubes 7, six of which are usually provided, are each enclosed within an outer casing or combustion chamber 8, to which air is supplied by a compressor 9 (shown in phantom lines in Fig. 1).

The vapourizer tubes 6, also in accordance with the usual practice are mounted in groups of six tubes in tube plates 10; such a group of vapourizer tubes mounted in its tube plate 10 is supported in each flame tube 7 by a transverse baffle 11. The vapourizer tubes extend downstream of the baffle into the flame zone in which combustion takes place. Upstream of the baffle, the flame tube 7 forms a plenum chamber 12 open at its forward end to the air which enters the combustion system from the compressor 9 in the direction of the arrow A. Air from the chamber 12 enters the upstream ends of the vapourizer tubes 6, which ends protrude forwardly through the tube plate 10, and the air passes down the tubes into the flame zone; other air passes down space 13 between the flame tube 7 and its outer casing, to enter the combustion zone through holes 14.

In accordance with the invention, the burner 5 is preferably centrally mounted on the tube plate 10 adjacent the open upstream ends of the vapourizer tubes 6, and it comprises a body 15, a jet unit in the form of a plate 16 having a plurality of jet elements 17 equal in number to the number of vapourizer tubes 6, and a nozzle assembly including a multiple nozzle block 18. The burner 5 is supplied with fuel from an external source through a pipe 19.

The fuel supply pipe 19 enters the body 15 through a hollow boss 20 which opens into a

cylindrical chamber 21. Leading out of the chamber 21 and symmetrically disposed around the axis of the burner is a number of longitudinal flow passages 22 equal to the number of jets required; the flow passages 22 are preferably of circular cross-section and they extend to the front face of the body.

Each jet element 17 consists of a small cylindrical plug having an orifice axially drilled therein and being a light push fit in a housing 18^a provided in the jet plate 16; the assembly of the jet plate and its associated jets is best seen in Fig. 4. The jet plate 16, having a plurality of jet elements 17, is clamped between the body 15 and the multiple nozzle block 18 by a central bolt 23 which is screwed into the core 15^a of the body. Thin compressible sealing washers 24 are provided between the body 15 and the jet plate, and between the jet plate and the multiple nozzle block 18.

The forward portion of the multiple nozzle block 18 is formed to provide a plurality of nozzles 25 extending forwardly and outwardly from the face of the block 18 and opening out of nozzle passages 26 extending obliquely through the block from the rear face thereof. Each nozzle 25 corresponds to one of the jet elements 17 and is directed to one of the vapourizer tubes 6.

In assembly, the longitudinal flow passages 22 in the body are aligned with the jet elements 17 and with the nozzle passages 26 to provide metered conduits from the chamber 21 to the open ends of the vapourizer tubes 6. The thickness of the said jet plate is substantially the same as the length of each jet element so that the faces of the jet elements, when assembled in the jet plate, are flush with the faces of the said plate. The outside diameter of each jet element is little greater than the diameters of the corresponding longitudinal flow passage 22 and of the corresponding nozzle passage 26; consequently when the jet assembly is clamped between the washers 24, the jet elements are securely held against longitudinal movement or leakage around their peripheries. To minimize the obstruction to the entry of air into the tubes from the plenum chamber 12, the burner is set centrally among the tubes and sprays fuel obliquely into their open ends.

In order to provide the required accuracy of performance of the jet elements 17, it is necessary that their manufacture should be controlled within very fine limits and that the surfaces not only of the bores but also of the inlet and outlet faces should be highly finished. It is also important that the jet elements should not be subjected to any distortion during assembly. It will be appreciated that the simple construction according to this invention enables the inlet and outlet faces to be readily polished. The light push fit assembly in the jet plate 16 together with the positive longitudinal location achieved by the simple clamping action aforementioned, provides a mounting for the jets which is free from the risks of distortion inevitably present in the screwed mounting commonly used. Moreover, the construction of the burner is such that the jet elements are well protected against accidental damage by virtue of their situation inside the burner assembly, although the whole burner can be readily dismantled for cleaning or for the replacement of jet elements by removing the single central bolt 23.

In the operation of the burner, fuel is introduced to the burner through the pipe 19 and flows into

the chamber 21 and the flow passages 22 and through the calibrated jet elements 17 to the nozzles 25, whence it is introduced into the vapourizing tubes 6. The air flowing through the tubes carries the fuel with it into the hot region of the tubes, where the liquid fuel is vapourised by the heat of combustion, and the mixture of air and fuel vapour is discharged into the combustion zone as a combustible gas. It will be readily understood that to achieve a uniform distribution of the flame in the combustion zone, the discharge of the gases from the individual vapourizer tubes must be uniform. To this end the jet orifices are carefully calibrated before assembly to allow the passage of a given quantity of fuel within a given time at a given entry pressure and, according to this invention, this calibration may be maintained within very close limits so that, at any given fuel pressure, a substantially equal flow of fuel will be delivered through each jet to each vapourizer tube.

It will be understood that the form of the invention herewith shown and described is to be taken as a preferred example of the same and that various changes in the shape, size and arrangement of the parts may be adopted, without departing from the spirit of the invention or the scope of the claims.

What I claim as my invention is:

1. A burner for injecting liquid fuel into a vaporizing combustion system comprising a body having a flat forward face and a flow passage passing through the body and the said face, a nozzle block having a flat rearward face and providing a nozzle, the nozzle block having a nozzle passage extending from the rearward face through the nozzle, a jet plate located between the flat faces of the body and the nozzle block, the jet plate having flat opposite faces and a jet orifice extending therethrough and communicating with the said passages, the jet orifice being cross-sectionally smaller than the flow passage and than the nozzle passage to limit the rate of flow through the said passages, and means for removably securing the jet plate between the body and the nozzle block.

2. A burner for injecting liquid fuel into a vapourizing combustion system, comprising a body having a flow passage extending through it, a nozzle having a nozzle passage extending through it, a jet plate having flat opposite faces disposed between the body and the nozzle and having a housing aperture extending through it, and a jet element disposed wholly within the housing aperture between the opposite faces of the jet plate, the jet element also having flat opposite faces and having an orifice extending between the last-mentioned faces from the flow passage to the nozzle passage to conduct the fuel between the said passages, the orifice in the jet element being smaller than the flow passage and smaller than the nozzle passage and thus providing a flow-limiting constriction determining the rate of flow through the said passages.

3. A burner for injecting liquid fuel into a vapourizing combustion system comprising a body having a cylindrical flow passage through it, a nozzle spaced from the body and defining a cylindrical nozzle passage, a jet plate disposed in the space between the body and the nozzle and having a housing aperture extending through it, and a cylindrical jet element in the housing, the jet element having an axial orifice registering with the said passage, the diameter of the jet element being greater than the diameter of the flow pas-

5

sage and than the nozzle passage and the orifice in the jet element being cross-sectionally smaller than the flow passage and than the nozzle passage and thus providing a flow-limiting constriction determining the rate of flow through the 5 said passages.
